UNITED STATES PATENT OFFICE

120,516

DESIGN FOR A SHOE

John Roman, Winchester, Mass., assignor to Trimmings, Inc., Lawrence, Mass., a corporation of Massachusetts

Application February 28, 1940, Serial No. 90,584

Term of patent 3½ years

To all whom it may concern:

Be it known that I, John Roman, a citizen of the United States, residing at Winchester, in the county of Middlesex and Commonwealth of Massachusetts, have invented a new, original, and ornamental Design for Shoes, of which the following is a specification, reference being had to the accompanying drawing, forming part thereof.

The drawing is a perspective view of a shoe showing my new design.

I claim:

The ornamental design for a shoe, substantially as shown.

JOHN ROMAN,
